UNITED STATES PATENT OFFICE.

ALBERT B. CONANT, OF NEWTON CENTER, AND LEONARD A. HOUSE, OF BOSTON,
MASSACHUSETTS.

FLUID-GOVERNED ELECTRIC SWITCH.

Application filed January 3, 1921. Serial No. 434,726.

To all whom it may concern:

Be it known that we, ALBERT B. CONANT, a citizen of the United States, residing at Newton Center, in the county of Middlesex and 5 State of Massachusetts, and LEONARD A. House, a citizen of the United States, residing at Boston, in the county of Suffolk and State of Massachusetts, have invented an Improvement in Fluid-Governed Electric 10 Switches, of which the following is a specification.

This invention relates to fluid-pressure controlled electric switches of the type adapted automatically to control the operation of an electrically-operated fluid pump to maintain fluid pressure, or fluid-level, in a tank or reservoir between predetermined 15 limits.

Fluid-pressure controlled electric switches 20 of the type above set forth usually include a movable switch member and a piston governed by a fluid-pressure actuated diaphragm to operate the switch member. The range of movement of the diaphragm, usually 25 a large disc, between the predetermined pressure limits is relatively small and the speed of movement is practically imperceptible. Consequently quick-acting means have been employed intended rapidly to move the switch 30 member between open and closed positions upon a predetermined range of movement of the pressure-governed piston. Such means has usually been a tensile spring or equivalent connected between the movable switch member and a lever governed by the piston arranged to be moved from one to the other 35 side of the pivotal center of the movable switch member to move it between open and closed positions. Due to the extremely slow 40 movement of the piston, as when pressure is being built up in a tank, the axis of the tensile spring may be positioned substantially in line with pivotal center of the switch member for a considerable period of time 45 without being sufficiently eccentric therewith to move the switch member to open position.

With such a condition there is practically no, or at least insufficient, pressure between the stationary and movable switch members 50 and arcing occurs; and the arcing may be accentuated because of the vibration of the switch and its support, and also because of the pulsation of the diaphragm piston at each stroke of the pump piston. Very frequently the stationary and movable switch

members are welded together so that the switch can not open, and if the automatic safety valve of the pump does not open, and it often fails to open, either the motor burns out or the pressure tank bursts. 60

An object of this invention is to provide a switch of the type above set forth with means whereby it is constrained rapidly to move between open and closed positions and will be strongly retained in closed position until 65 rapidly moved to open position; and, further, will not remain in a semi-open or "dead center" position.

A switch embodying this object of the invention may include a pivoted movable 70 switch-member, an operating lever, and a tensile spring connecting said lever and movable switch member. Said lever may be arranged to be actuated by the pressure governed piston through a lost-motion connection and means may be provided by which 75 said lever is moved rapidly from one side to the other of its pivot whereby rapidly to shift the tension of said spring from one to the other side of the pivot of the movable 80 switch member thereby to cause it rapidly to move between open and closed positions. Said means may, and preferably does, comprise the eccentric pivoting of said lever and movable switch member or it may comprise 85 a second spring connected with said lever and a fixed support arranged to be moved across the pivot of said lever subsequently to move the spring connected with the movable switch member across the pivot of said 90 switch member.

The pressure-governed means has usually comprised a flat disc or diaphragm. In order to obtain a sufficient motion, the diaphragm is of considerable diameter and consequently the mechanism connected therewith is subjected to considerable pressure; and the mechanism must have relatively great strength and consequently be relatively massive. 95

A further object of the invention is the provision of a novel pressure-governed means or diaphragm adapted to have a relatively great range of movement between the predetermined pressure limits for a relatively small total pressure to which it is subjected, whereby the mechanism associated therewith may be of little mass and the action the more rapid. The small total pressure acting upon the components of the device re- 105 110

sults in greatly reduced friction and consequently the accuracy of the device is enhanced.

The pressure governed means or dia-
5 phragm embodying my invention may com-
prise an elastic fluid-imperforate tube en-
closed in a spring-coil casing adapted for
fluid communication through its open end.
An increase in fluid pressure will operate to
10 expand the tube axially against the pres-
sure of its spring casing, and the casing will
assist the tube to contract axially upon a re-
duction of internal fluid pressure. The
spring casing will resist lateral expansion of
15 the tube.

A further object is generally to improve
the construction and operation of fluid-pres-
sure and fluid-level governed electric
switches.

20 Fig. 1 is a side elevation of a fluid pres-
sure governed electric switch embodying
our invention, the enclosing casing being
broken away.

Fig. 2 is a rear elevation of Fig. 1.
25 Fig. 3 is a plan view of Fig. 1.

Fig. 4 is a front elevation of Fig. 1, illus-
trating more particularly the stationary and
movable switch members.

Fig. 5 is a vertical section along line 6—6
30 of Fig. 3, illustrating the diaphragm tube
in expanded and the switch in open position.

Fig. 6 is a detail in side elevation, of the
mechanism on the point of moving the mov-
able switch member into open position.

35 Fig. 7 is a side view of a modified form
of the invention adapted for fluid-level, or
float, control.

Fig. 8 is an enlarged detail of the mov-
able switch member and illustrates more
40 particularly the pivotal connection of the
supporting bar for the bridging members
with the frame of the movable switch
member.

As here shown the fluid-pressure gov-
45 erned switch embodying the invention in-
cludes the base 10 adapted to be supported
by the pipe 11, by which fluid connection
is made with the pressure source as a tank
or pump not shown. A standard or sup-
50 porting-plate 12 extends above the base 10
and is adapted to support the switch mem-
bers and the operating mechanism therefor.
A casing 13 may enclose all mechanism and
the side-walls thereof may be received in the
55 groove 14 in the base 10. A U-shaped mem-
ber 15 may be secured to the opposite ends
of said plate 12 and extend upwardly there-
above in which the screw 16 carried by the
casing 13 may be threaded, thereby to se-
60 cure the casing in place.

The diaphragm embodying our invention
comprises the fluid imperforate tube 17
formed of soft rubber or the like of rela-
tively small internal diameter as contrasted
65 with its length. The upper end of the tube

is closed by the thickened and conically
shaped upper end portion 18; and the lower
end portion is formed with the outwardly
extended flange 19 preferably somewhat
thicker than the walls of the body of the
70 tube. Preferably also, the lower portion
of the tube adjacent the flange 19 is thick-
ened internally for strength as indicated at
20. A spring-coil casing 21, the con-
volutions of which, in the contracted condi-
tion of the tube, preferably contact, encloses
the tube and serves to support the tube
against lateral deformation. The upper end
75 of the casing is shaped to conform to the
end of the tube and has the loop 22 by which
to connect with the switch operating mecha-
nism hereinafter to be described.

Said tube is vertically disposed on and
has its flanged end received in and sup-
ported on the bottom wall 23 of an inter-
nally screw-threaded recess 24 in a boss 25
of the base 10 and said pipe 11 is adapted
80 to be in fluid communication with said re-
cess and the interior of said tube. The
flange 19 of said tube is compressed against
the bottom wall 23 of said recess 24 by the
collar 26 disposed over said tube and its
85 spring-casing and threaded in said recess.
Said collar is internally screw-threaded to
receive the end-convolutions of said cas-
ing by which said casing and collar are fixed
90 together. The tube 17 is thereby secured
at its open end only and is free to expand
along its length. In expanding, under pres-
sure, the convolutions of the casing will
95 separate, as illustrated in Fig. 6 yet the ex-
tent of separation will be relatively small
for the extreme axial expansion of the tube
and the side walls of the tube will be amply
100 supported by the convolutions of the spring-
coil against lateral deformation and pos-
sible rupture. The tube and its spring-cas-
ing are unsupported except at the lower end
105 and consequently friction between it and
other supporting members is absent so that
the axial movement of the tube may be pro-
portional to the pressure variation of the
fluid within the tube. Due to the small
110 cross-sectional area of the tube the total
pressure on the closed end thereof is rela-
tively small so that mechanism of small
mass may be employed and but little fric-
tion will result at the pivotal connections
115 between the components. The diaphragm
and its casing are also free to bend lat-
erally and expand or contract in any lat-
eral displacement whereby extreme accuracy
of alignment between it and the switch-op-
erating mechanism is unnecessary.

The switch adapted to be operated by
the tubular diaphragm above set forth is sup-
ported by and on the side of said supporting
plate 12 opposite from said diaphragm. A
double-pole switch is herein illustrated
which includes the two sets or pairs of 125
130

- stationary switch-members or studs 28 and 29 carried by the insulating plate 30 secured to the side face of said supporting plate 12. Said switch studs extend through apertures 5 in and are insulated from said supporting plate 12 and are provided at the rear with the binding-means 31 for connection with circuit leads adapted to be passed through insulating bushings 32 in the base 10.
- 10 Said supporting-plate 12 is formed with the slot 33 therein adapted to permit movement of a tension spring hereinafter to be described, and has two spaced arms or-ears 34 extended forwardly from the sides of 15 said slot adapted to support the movable switch member and the switch operating mechanism.
- The movable switch member includes the two spring bridging members 35 having the 20 contact tips 35^a thereon disposed in alignment with the stationary switch-members and secured by the screws 36 to the insulating bar 37. Said bar is carried by the depending frame including the two spaced arms 38 disposed 25 between the ears 34 of the fixed support and pivoted on the pins 39 fixed in said ears; and the intermediate connecting portion 40. Said connecting portion 40 has the downwardly extended ear 42 on one side and the 30 extension 43 on the other side of it; and said extension 43 has a portion 46' extended from it substantially parallel with the connecting portion 40. The insulating bar 37 is received between said portions 40 and 46', and 42 35 and 43 and is spaced from said latter portions 42 and 43 and is pivotally supported on the rivet 41 which extends between and is fixed to said portions 40 and 46'. This arrangement facilitates the engagement of the 40 bridging members with the stationary switch members. Said portions 42 and 43 prevent undue rocking of the bar 37. Said portion 43 extends beyond the bar and has the slot 44 therein in which the body of a stop-screw 45 45 is received. Said screw is removably secured in the supporting-plate 12 and its head 45^a is adapted to engage said portion 43 whereby to limit the movement of the movable switch member. The switch-open 50 position of the movable switch-member determines to some degree the low pressure at which the device will operate to close the motor circuit associated therewith; and the greater the distance of the movable 55 switch member away from the stationary switch member, the lower will be the pressure at which the switch will be closed, and vice versa. For some purposes it may be desirable to arrange said screw 45 to be adjustable toward and away from said supporting plate 12 whereby to vary the switch closing pressure but, in many instances, this is not desirable and an unintelligent adjustment of said screw 60 65 may destroy the quick acting properties of the switch. Said intermediate portion 40 is also formed with the upwardly extended ear 46 having the aperture 47 therein in which the lower end 48 of a tensile spring 49 is received by which the movable switch member is moved rapidly between open and closed positions.
- Means are provided by which the other end of said spring is supported which admits of its being moved in both directions 70 across the pivotal center of said movable switch member whereby to exert a spring pressure either to press the movable switch member forcibly against the stationary switch members or to pull the movable switch member into open position. Said supporting means comprises the vertically disposed or inverted U-shaped frame having the downwardly extended arms 50 pivotally supported on pins 51 carried by the ears 34 to the rear of the pins 39 and having the connecting portion 52 formed with the aperture 53 therein in which the upper end of said spring 49 is connected.
- In the more or less ordinary construction of fluid pressure governed switches, said arms 50 and arms 38 of the movable switch-member are concentrically pivoted with the result that when the ends of the spring and the pivot are in alignment there is practically no spring pressure on the movable switch member to maintain it in closed position; consequently arcing occurs. It is an important object of this invention that said arms 50 and 38 be eccentrically pivoted, as 80 shown, whereby the movable switch member can not be maintained in a dead-center position without positive tendency to move in either direction, as will hereinafter be explained.
- The movements of said frame supporting the upper end of said spring 49 are controlled by a tripping frame having the horizontally and rearwardly extended arms 55 concentrically pivoted with said arms 50 on 90 said pins 51. Said arms 55 are reflexed inwardly toward each other over and on opposite sides of the loop-portion 52 of the spring-casing 21 of the tube diaphragm; and a pin 56 passed through said loop and 100 apertures in said arms 55 serves to connect said arms to said diaphragm for movement. Said frame is formed also with the arms 57 which extend upwardly beyond said arms 50 and have the oppositely disposed-inwardly-directed ears 58. Said ears are so spaced that the spring supporting frame is permitted a considerable amount of independent movement, due to said spring 49, from one to the other side of its pivot, for the purpose of rapidly shifting the upper end of said spring from one to the other side of the pivot of the movable switch member.
- The disposition of the components of the device when the tube diaphragm is sub- 110 115 120 125 130

jected to but little pressure is as illustrated in Fig. 1; and the switch is closed and the pump may operate to increase the pressure in a storage tank.

5 As the fluid pressure increases the diaphragm expands axially and the convolutions of the spring-casing 21 separate as indicated in Fig. 6. The tripping frame is slowly rotated in a clockwise direction about 10 its pivots 51 and moves the spring-supporting frame with it, thereby gradually moving the ends of the spring into alignment with said pins 51. At some fluid pressure the spring-supporting frame will be moved 15 to a position indicated in Fig. 6, wherein the ends of the spring and the pivot of said frame are substantially in alignment, and the frame is about to be pulled over by the action of the spring. In this condition, 20 however, the spring is so eccentrically disposed with relation to the pivot of the movable switch member that said switch member is positively held in closed position. When the spring-supporting frame is moved 25 slightly forward, the spring will be moved across the pivot of said frame and its tension will be exerted to move it rapidly to its extreme forward position against the forward stops 58 of said tripping frame. 30 During its rapid forward movement, said frame will move its end of said spring rapidly across the pivot of the movable switch member and the tension of the spring will be rapidly shifted from a switch-closing tension 35 to a switch-opening tension, and consequently the movable switch member will be moved rapidly into open position. It will be noted that, with proper arrangement of the mechanism, there will be no point at 40 which the movable switch member is held for an appreciable time without tendency either to move toward open or closed position.

In the modification illustrated in Fig. 7, 45 the switch is arranged for operation by a float 70 and for this purpose the tubular diaphragm is replaced by the lever 71 pivoted to the base 10 and arranged to be engaged by the stops 72 attached to the float 50 cable 73. Said lever is connected through the link 74 with the switch mechanism; and the operation of the switch is the same as 55 with the tubular diaphragm.

The operation of the device as the pressure is reduced and the diaphragm contracts axially, is essentially the same.

It is obvious that the invention may be embodied in other structures than those herein set forth.

60 We claim:

1. An electric switch having the combination of stationary and movable switch members, a fixed support having two spaced and extended arms, said movable switch member 65 including two spaced and connected arms

disposed between the arms of said fixed support, means pivotally connecting said arms, and switch operating mechanism including an operating frame having spaced and connected arms, means pivotally connecting the 70 arms of said frame to the arms of said fixed support to the rear of the pivotal connection of the arms of said movable switch-member, a spring disposed between all of 75 said arms and connected to said movable switch member and operating frame, and means to move said operating frame comprising a lever pivotally supported on the pivotal support for the operating frame having inturned ears between which an arm 80 of said operating frame is loosely received.

2. An electric switch having the combination of stationary and movable switch members, a fixed support having two spaced and extended arms, said movable switch member 85 including two spaced and connected arms, disposed between the arms of said fixed support, means pivotally connecting said arms, and switch operating mechanism including an operating frame having spaced and connected arms, means pivotally connecting the 90 arms of said frame to the arms of said fixed support to the rear of the pivotal connection of the arms of said movable switch-member, a spring disposed between all of 95 said arms and connected to said movable switch member and operating frame, and means to move said operating frame comprising a lever pivotally supported on the pivotal support for the operating frame having 100 lost-motion connection therewith.

3. An electric switch having the combination of stationary and movable switch members, a fixed support having two spaced and extended arms, said movable switch member 105 including two spaced and connected arms disposed between the arms of said fixed support, means pivotally connecting said arms, and switch operating mechanism including an operating frame having spaced and connecting arms, means pivotally connecting 110 the arms of said frame to the arms of said fixed support to the rear of the pivotal connection of the arms of said movable switch-member, a spring disposed between all of 115 said arms and connected to said movable switch member and operating frame, and means to move said operating frame comprising a lever pivotally supported on said fixed support having lost-motion connection 120 with said operating frame.

4. An electric switch having the combination of stationary and movable switch members, a fixed support having two spaced and extended arms, said movable switch member 125 including two spaced and connected arms disposed between the arms of said fixed support, means pivotally connecting said arms, and switch operating mechanism including an operating frame having spaced and con- 130

nected arms pivoted to the arms of said fixed support to the rear of the pivotal connection of the arms of said movable switch member, a spring disposed between all of 5 said arms and connected to said movable switch member and operating frame, and means to move said operating frame having lost-motion connection therewith.

5. An electric switch having the combination of stationary and movable switch members, a fixed support having two spaced and extended arms, said movable switch member including two depending, spaced and connected arms disposed between and 10 pivotally connected at the upper ends thereof to the arms of said fixed support, and switch operating mechanism including a vertically disposed operating frame having spaced and connected depending arms, means 15 pivotally connecting the arms of said frame to the arms of said fixed support to the rear of the pivotal connection of the arms of said movable switch member, a spring disposed between all of said arms and connected to 20 said depending movable switch-member and vertically disposed operating frame, and means to move said operating frame comprising a lever pivotally supported on the pivot of said operating frame and having 25 lost-motion connection with said frame.

6. An electric switch having the combination of stationary and movable switch members, a fixed support having two spaced and extended arms, said movable switch member including two depending, spaced and connected arms disposed between and 30 pivotally connected at the upper ends thereof to the arms of said fixed support, and switch operating mechanism including a 35 vertically disposed operating frame having spaced and connected depending arms pivoted to the arms of said fixed support to the rear of the pivotal connections of the arms of said movable switch member, a spring disposed 40 between all of said arms and connected to said movable switch member and operating frame, and means to move said operating frame having lost-motion connection therewith.

50 7. An electric switch having the combination of stationary and movable switch members, said movable switch member including two spaced and connected arms, means pivotally supporting said arms at the ends 55 thereof, and switch operating mechanism including an operating frame having two spaced and connected arms, means pivotally supporting the arms of said frame at the ends thereof and eccentrically with respect 60 to the pivotal supports of the arms of the movable switch members, a spring disposed between the arms of and connected to said movable switch member and operating frame, and means to move said operating frame to move said spring across the pivots 65

of said operating frame whereby to effect continued movement of said frame under influence of said spring alone.

8. An electric switch having the combination of a fixed support, stationary switch-members carried thereby, a movable switch-member comprising a pivoted arm, and an insulated bridging member for the stationary switch members carried by said arm, and operating means for said movable switch member comprising a pivoted operating arm, a spring connecting said operating arm and the arm of the movable switch member and movable across the pivots of both of said arms, and means to move said operating arm to move said spring across the pivot of said arm whereby to effect continued movement of said arm under influence of said spring alone.

9. An electric switch having the combination of a fixed support, two pairs of stationary switch-members carried thereby, a movable switch member comprising a pivoted arm, an insulating bar carried by and extended laterally on opposite sides of said arm, bridging members for each pair of stationary switch members carried by said insulating bar on opposite sides of said arm, and operating means for said movable switch member comprising a pivoted operating arm, a spring connecting said operating arm and the arm of the movable switch member and movable across the pivots of both of said arms, and means to move said operating arm to move said spring across the pivot of said arm whereby to effect continued movement of said arm under influence of said spring alone.

10. An electric switch having the combination of a fixed support, two pairs of stationary switch-members carried thereby, a movable switch-member comprising a pivoted arm, an insulating bar carried by and extended laterally on opposite sides of said arm, means pivotally connecting said bar with said pivoted arm for restricted angular movement transverse the plane of said pivoted arm, bridging members for each pair of stationary switch members carried by said insulating bar on opposite sides of said arm, and operating means for said movable switch member comprising a pivoted operating arm, a spring connecting said operating arm and the arm of the movable switch member and movable across the pivots of both of said arms, and means to move said operating arm to move said spring across the pivot of said arm whereby to effect continued movement of said arm under influence of said spring alone.

11. An electric switch having the combination of a fixed support, two pairs of stationary switch-members carried thereby, a movable switch-member comprising a pivoted arm, an insulating bar carried by and

extended laterally on opposite sides of said arm, means connecting said bar loosely with said pivoted arm arranged to permit it to move angularly with respect to said pivoted 5 arm, bridging members for each pair of stationary switch-members carried by said insulating bar on opposite sides of said arm, and operating means for said movable switch member comprising a pivoted operating arm, 10 a spring connecting said operating arm and the arm of the movable switch member and movable across the pivots of both of said arms, and means to move said operating arm to move said spring across the pivot of said 15 arm whereby to effect continued movement of said arm under influence of said spring alone.

12. An electric switch having the combination of a fixed support, stationary switch-

members carried thereby, a movable switch- 20 member comprising a pivoted arm, a bridging member for said stationary switch members, and means loosely connecting said bridging member with said arm, and operating means for said movable switch-member 25 comprising a pivoted operating arm, a spring connecting said operating arm and the arm of the movable switch member and movable across the pivots of both of said arms, and means to move said operating arm 30 to move said spring across the pivot of said arm whereby to effect continued movement of said arm under influence of said spring alone.

In testimony whereof, we have signed our 35 names to this specification.

ALBERT B. CONANT.
LEONARD A. HOUSE.
